UNITED STATES PATENT OFFICE.

EDWARD A. KRAMER, OF NEW YORK, N. Y.

DESIGN FOR A BOTTLE.

SPECIFICATION forming part of Design No. 20,567, dated March 10, 1891.

Application filed December 26, 1890. Serial No. 375,871. Term of patent 3½ years.

To all whom it may concern:

Be it known that I, EDWARD A. KRAMER, a citizen of the United States, residing at New York city, in the county and State of New

5 York, have invented and produced a new and original Design for a Bottle, of which the following is a specification, reference being had to the accompanying photograph, forming part thereof, which represents a bottle shaped 10 in accordance with my design.

The principal feature of the design consists 15 of a body figure A, simulating an ear of corn, and a handle figure A', which appears as if formed by a curvature in a portion of the husk of the ear. The minor decorations of 20 the body figure are the lines a, indicating a

break in the husk, and kernel figures a', disclosed by the break. In connection with the body figure is a stopper figure D, also simulating an ear of corn.

I claim—

The design for a bottle, consisting in the body representing an ear of corn with its husk partially removed from over the grain and another portion of the husk bowed from the 25 body to present a handle-like appearance, as shown and described.

EDWARD A. KRAMER.
